COOKING STOVE AND RANGE
CONSTRUCTION

Jacob Teller, New Rochelle, N. Y., and Arthur P. Schulz, Rockford, Ill., assignors to Teller Stove Designing Corporation, New York, N. Y., a corporation of New York

Original application December 13, 1932, Serial No. 647,036. Divided and this application October 23, 1934, Serial No. 749,628

8 Claims. (Cl. 126—340)

This invention relates to cooking stove and range construction, and is a division of our original application Serial No. 647,036, filed December 13, 1932.

The particular features of the present invention reside in the specific oven structure, and in the arrangement of the cooking vessel rack, whereby said rack, pivoted upon a vertical axis within the oven compartment, may be interconnected with the oven door in such manner that, when the door is opened, the rack is oscillated upon the pivots, and the supports for the cooking vessels carried thereby moved out of the oven into a position conveniently accessible to the person using the range.

A further feature resides in mechanism carried by the oven door and selectively connectible with the swinging rack, to the end that the oven door may be opened or closed with or without simultaneous operation of the rack.

These and many other features of advantage will be apparent to those familiar with the operation of such apparatus, and the various objects will become quite evident upon reference to the accompanying drawings and specification.

In the accompany drawings:

Fig. 1 is a front perspective view of one form of the invention, and showing the oven doors open;

Fig. 2 is a vertical transverse sectional view of a preferred form of the range on substantially the line 2—2 of Fig. 3, showing the oven door open;

Fig. 3 is an enlarged perspective detail view of the oven section of the range, with the door open to illustrate the rack and door structure with co-operative mechanism;

Fig. 4 is a vertical sectional view through a portion of the door on substantially the line 4—4 of Fig. 3.

Fig. 5 is a detail sectional view through the rack support.

Fig. 6 is a horizontal section taken through the range on substantially the line 6—6 of Fig. 3, and

Figure 7 is a detail view similar to Fig. 4, but showing the parts arranged so that the shifter plate renders the door and rack parts relatively inoperative.

Referring now to the drawings by numerals of reference, 1, designates generally the range, having the usual sides 2, back wall 3, and the front, which latter is closed by a series of doors and panels indicated at 4, 5, 6 and 7 respectively.

The insulated cooking top 8 of enameled sheet metal or other suitable material, has therein, a plurality of openings 9, according to an arrange-

ment peculiar to this invention, the particular function of which will be apparent as the description advances, and as more particularly set forth in our original application hereinbefore referred to.

Specifically, the openings 9 are arranged in the form of the letter L, the long leg of which lies toward and parallel with the rear edge of the cooking top 8, while the shorter leg lies adjacent to and parallel with the right hand edge of the cooking top 8 thus providing a rectangular working top space 10, surrounded on two sides by the series of openings 9, beneath which are suitably supported the burners 11, said openings having utensil supporting grids 12.

Referring at this time to Figures 2 and 6, it will be observed that the range is divided into a plurality of compartments 14 and 15, the former constituting the combined oven and broiler compartment, while the latter constitutes an L-shaped space which underlies the openings in the cooking top, and in the upper portion of which L-shaped compartment, are suitably supported the burners 11.

These compartments 14 and 15, are defined by a longitudinal insulated partition 16 and a transverse insulated partition 17, the latter terminating short of the back wall 3 of the range, each of the partitions terminating at a point above the bottom 18 of an auxiliary compartment 19 which is provided with trackways 20 for a sliding drawer 21, the front of which latter takes the form of the panel 6, above referred to.

As distinguished from ovens of the usual character, the present oven compartment 14 is elongated in form, and relatively shallow as shown in Figure 6, the greater length being in the direction of the width of the range as shown. By this arrangement and form of oven, we are able to obtain an oven of a capacity substantially that of an oven such as employed in the usual range, in which it extends throughout the depth of the range body.

At the same time, as distinguished from ranges of the ordinary type, the top of the oven extends up to the cooking and working top, without the intervention of the regular burner compartment. This of course, is permitted through the arrangement of the series of burners to the side and back of the upper portion of said oven.

By the arrangement shown, not only are the burners so positioned that they permit elevation of the oven and broiler compartment 14 to an accessible working position, but at the same time, an insulated working space 10, convenient to

the burners and oven interior racks is provided. The cooking top is provided with a rear fence or splash back 22.

The range front, includes a frame 23, having necessary openings which are closed by the several panels and doors above mentioned, the door 4 serving as the oven and broiler compartment closure, the panel 6 as the closure for the compartment containing the sliding drawer 21, the door 5 as the closure for an auxiliary compartment which may serve for any purpose for which it may be intended, and the panel 7, on which are mounted the handles for the burner valves or for electric switches, when the range is utilized as an electric cooking apparatus.

These panels and doors have their adjacent edges in substantially abutting relation, their outer surfaces being in substantially the same plane and presenting a plain flush outer face. The outer lateral edges of the several doors and panels, preferably extend to the side edges of the frame 23 so that no parts of the latter are visible.

The particular features of the present invention reside in the oven and broiler compartment rack and operating mechanism, more clearly shown in Figures 3, 4 and 7. Referring especially now to Figures 3 and 5, it will be observed that there is provided a rack support comprising a vertical rectangular sheet metal frame 24 which has at its upper and lower corners, at one side of said frame, a pair of bearing pins 25 and 26 respectively which pins have their bearings in the upper and lower top and floor plates 27 and 28 respectively of the oven compartment 14, permitting the rack to be swung in an arc of a circle within said oven.

It is to be particularly noted that the bearings for the rack are positioned on an axis located forward of and at one side of the oven compartment, as more clearly illustrated in Figure 6, or in other words at a point closely adjacent the corner of said oven in proximity to the oven door hinge, for purposes which will be presently observed.

Specifically, the sheet metal frame 24 has its side frame members 30 provided with a vertical series of recesses 31 formed by punching through the sheet metal frame members in opposite directions at spaced intervals to provide a vertical series of lips 32, which cooperate with a finger or hook 33 and brace 35 to maintain the said tray support in proper position upon the swinging rack. The broiler pan which is removably mounted upon the support 34 is shown at 36, while an additional cooking vessel rack is shown at 37, the latter also being removably supported upon the swinging rack by means similar to that for the broiler pan support.

As will be more clearly observed from an inspection of the view in Figure 6, in which the movable parts are shown in full and dotted lines, the arrangement of the mounting of the swinging frame is such that it may be conveniently swung from a position entirely within the oven, to a position such that the pans and supports carried thereby may be moved entirely out of the oven.

The rack is so constructed, that it may be operated either through an operative connection with the oven door 4, or independently thereof, and to this end, we provide the selective mechanism to be now described.

Rigidly attached to the lower corner of the rack 24, on the axis of the lower bearing 26 is a spring metal arm 38, which lies substantially

parallel with the long side of the pan support 34, said arm at its outer end having a lateral stud 40 carrying a pair of anti-friction rollers 41, which are adapted, when desired, to cooperate and ride in the channels 42 of a guide member 43 rigidly secured to the inner face of the door 4 toward its lower edge.

By this construction, it will be manifest that when the door is closed and opened, the rollers 41 on the end of the spring arm 38 may ride in the channeled guide member 43, resulting in the swinging of the rack 24 to bring the supports carried thereby, into and out of the oven simultaneously with the movements of said door.

At times, it may be desired to open or close the oven door 4 without at the same time swinging the rack 24, and to permit of such operation, we provide a selective mechanism shown particularly in Figure 4. This mechanism comprises a lever 44 pivoted intermediate its ends on a pin 45 carried by a bracket 46 fixedly secured to the opposed inner faces of the spaced plates forming the door 4.

At its lower end, this lever is provided with an inclined shifter-plate 47, which as shown in Fig. 25 normally extends through an opening 50 in the inner plate of the door and is disposed outside the space between said door plates due to the action of a coiled spring 48, the upper portion of one leaf of which engages the upper end of lever 30 44 and urges it into the position indicated in Fig. 7. In such position, the shifter plate extends over the entrance to the guideway member 43, and guides the rollers 41 on the arm 38 over, instead of into said guideway.

Under normal operating conditions, the parts are in the position shown in Fig. 7, that is, with the shifter plate 47 projected so that the rear edge thereof extends over the entrance to the channeled guide member 43. As now positioned, when the door is opened, the said anti-friction rollers 41 will ride up the inclined face of the shifter plate and clear the channels of the guide member, and there then being no operative connection between the door and rack at this time, the door may open without imparting any movement to said rack and the parts carried thereby.

However, when it is desired to cause the simultaneous operation of the rack and door, that is to have the rack swing out of the oven when the door is opened, the operator by pulling downwardly on the handle 52, causes the inner end to engage the upper end of the lever 44, moving said lever on its pivot 45 against the action of the spring 48 from the full line position shown in Fig. 7 to the full line position shown in Fig. 4, at which time, the rollers 41 will be permitted to ride into the entrance 51 of the channeled guideway 43. Opening of the door 4 outwardly into the position shown in Fig. 3 where ready access may be had to the articles disposed upon the racks or broiler. Referring to Fig. 2, the broiler burner is shown at 60 and the oven burner at 61.

While it is preferred to impart swinging movement to the rack through the connections with the door as hereinbefore described, the rack may be swung independently of the door. Thus, as indicated in Fig. 1, wherein the door 4 swings about a horizontal axis, the rack or frame 24 may be swung into and out of the oven compartment by hand.

What we claim is:

1. A range construction comprising a body having an oven compartment, a swinging rack comprising a vertically disposed rectangular sheet

metal frame, said frame being provided with vertically aligned bearing pins at the upper and lower corners at one side thereof, said bearing pins engaging bearings in the top and bottom walls 5 of said oven compartment adjacent a front corner thereof, and means at each side of said frame for adjustably supporting cooking vessel supports.

2. A range construction comprising a body 10 having an oven compartment, a swinging rack pivotally mounted within said oven compartment on a vertical axis, an oven door, a guide member mounted upon said door, an arm having one end thereof connected with said rack in alignment 15 with said vertical axis, the other end of said arm having means for interlocking engagement with said guide member for effecting swinging movement of said rack upon opening and closing of said door.

20 3. A range construction comprising a body having an oven compartment, a swinging rack pivotally mounted within said oven compartment on a vertical axis, an oven door, a guide member secured to said door, an arm rigidly supported by 25 said rack and having means for interlocking engagement with said guide member, and mechanism supported by said door for selectively permitting or preventing interlocking interengagement of said means with said guide member.

30 4. A range construction comprising a body having an oven compartment, a swinging rack pivotally mounted within said oven compartment, an oven door, an open ended channeled guide member supported by said oven door, a shifter plate disposed adjacent the open end of said channeled 35 guide member, a spring arm rigidly secured to said rack and having means adjacent the free end thereof for interlocking engagement with said guide member, and means supported by said door for selectively moving said shifter plate to or from a position over the open end of said guide member to prevent or permit interlocking engagement 40 of said first means with said guide member upon opening of said door.

45 5. The construction defined in claim 4 wherein said last means comprises a spring normally urging said shifter plate to a position over the open end of said guide member, and a handled lever for moving said shifter plate to a position clear 50 of the open end of said guide member against the action of said spring.

6. A range construction comprising a body hav-

ing an oven compartment, a swinging rack pivotally mounted within said oven compartment, an oven door, an open ended channeled guide member secured to said door, a spring arm rigidly secured at one end thereof to said rack, rollers 5 carried by the opposite end of said spring arm and biased thereby toward said guide member, a shifter plate normally closing the open end of said guide member, and means carried by said door for selectively moving said shifter plate to a position 10 whereby said rollers will engage said guide member upon opening of said door for imparting swinging movement to said rack.

7. A range construction comprising a body having an oven compartment, a swinging rack pivotally mounted within said oven compartment, an oven door, an open ended channeled guide member mounted upon the inner face of said door, a spring arm rigidly secured at one end thereof to said rack, rollers carried at the free end of 20 said arm and biased thereby toward said guide member, means normally closing the open end of said guide member whereby said rollers will mov- 25 ably engage said guide member externally of the channels therein upon opening of the door, and selectively operable means supported by said door for moving said first means to a position to permit engagement of said rollers within said channeled guide member upon opening of the door for imparting swinging movement to said rack. 30

8. A range construction comprising a body having an oven compartment, a swinging rack pivotally mounted within said oven compartment, an oven door, an open ended channeled guide member secured to the inner face of said door, a lever 35 pivotally mounted within said door, a shifter plate carried by one end of said lever adjacent the open end of said channeled guide member, spring means engaging said lever for normally urging said shifter plate to a position to close 40 the open end of said guide member, manually operable means supported by said door for moving said lever against the action of said spring to position said shifter plate to clear the open end 45 of said guide member, and means connected with said rack and interengaging with said channeled guide member in the last mentioned position of said shifter plate for swinging said rack upon opening or closing of said door. 50

JACOB TELLER.
ARTHUR P. SCHULZ.
